UNITED STATES PATENT OFFICE.

FRED A. ENGH, OF JOHNSTOWN, PENNSYLVANIA.

FLUID-PRESSURE MOTOR.

1,373,415.

Specification of Letters Patent.

Patented Apr. 5, 1921.

Application filed January 15, 1919. Serial No. 271,324.

To all whom it may concern:

Be it known that I, FRED A. ENGH, a citizen of the United States, residing in the city of Johnstown, in the county of Cambria and State of Pennsylvania, have invented certain new and useful Improvements in Fluid-Pressure Motors; and I do hereby declare the following to be a full, clear, and exact description, such as will 10 enable others skilled in the art to which it appertains to make and use the same.

My invention relates generally to improvements in fluid-pressure motors with special reference to those of the rotary type 15 provided with a shaft having movable blades located diametrically in a slot therein, said shaft being located eccentrically within a cylindrical opening, against the inner sides of which the blades are adapted 20 to contact.

Fluid under pressure is introduced through entrance ports against one side of the blades causing them and the shaft to rotate, and after a partial revolution is exhausted through suitable exhaust ports and as the operation continues the shaft is rotated with considerable power and velocity.

My motor is shown as adapted to be used in connection with a boiler tube cleaner tool 30 but it will be understood that it may be used for any other apparatus for which it may be suited.

Having thus given a general description of my invention, I will now, in order to 35 make the matter more clear, refer to the annexed sheet of drawings which forms part of this specification and in which like characters of reference refer to like parts:

Figure 1 is a vertical sectional elevation 40 of my improved motor taken on the line I—I of Fig. 7 showing the flue cleaner tool attached thereto. Fig. 2 is a side elevation of the shaft with the blades or paddles inserted therein. Fig. 3 is a vertical sectional elevation of the motor casing taken on the line III—III of Fig. 7. Fig. 4 is a plan 45 view of the bushing for the lower end of the shaft. Fig. 5 is a transverse sectional elevation taken on the line V—V of Fig. 1. Fig. 6 is a transverse sectional elevation taken on the line VI—VI of Fig. 1. Fig. 7 is a transverse sectional elevation taken on the line VII—VII of Fig. 1. Fig. 8 is a transverse sectional elevation taken on the 50 line VIII—VIII of Fig. 1. Fig. 9 is a detail of the lower end of the operating shaft 55

and eccentric bushing with a curved fillet; and Fig. 10 is a view of the same with a beveled connection between the large and small portions of the shaft. 60

Referring now to the characters of reference on the drawings:—1 is the casing which is generally of compact cylindrical form, as illustrated, 2 is the cylindrical fluid-pressure or operating chamber eccentrically located, 3 is a main inlet port extending longitudinally of the casing, connecting with the interior of the upper end thereof and adapted to receive fluid under pressure, which may be supplied by a pipe or hose 70 connected to the internally screw-threaded end 16 fitted into the casing, 4 are a number of cross ports connected with the main port 3 and opening into the fluid pressure chamber 2, as illustrated. 5 is the main exhaust port extending longitudinally of the casing, as shown, 6 are the cross ports connecting the fluid pressure chamber with the main exhaust port 5, which latter opens to the outer atmosphere and is adapted to discharge the fluid which has been utilized therein. 7 is a bushing adapted to serve as a bearing for the lower end 26 of the shaft, 20 and also as a thrust bearing for the shaft, this bushing being provided with an eccentric flange 8, which flange is constructed and adapted to form the end of and the closure for the lower end of the fluid pressure chamber 2, and the seat therefor is of such form that it can be readily shaped by 80 drilling or reaming the bottom portion of said chamber, while the lower part of the bushing 7 is similarly cylindrical and adapted to closely fit into the lower end of the casing, as illustrated. The bushing 7 is provided with a groove 9 of approximately semicircular form and the adjacent portion of the casing also has a groove of the same shape opposite thereto to receive the pin 10, which holds the bushing in place and prevents the displacement or rotation of 90 same and also allows the bushing with the flange to be removed in case of wear, and a new bushing inserted in place thereof. The upper end of the shaft is journaled in 100 the bushing 11, which, as illustrated, is formed of a simple disk approximately circular in form, with the exception that it has openings therein to allow the entrance of fluid under pressure into the inlet port 110 3, and is also provided with a notch 14, in which is inserted a pin 15 to hold it in its

proper position so that the opening in the same registers with the inlet opening of the port 3. The disk or bushing 11 is also provided with a cylindrical opening 12, in which the upper reduced end 25 of the shaft 20 is journaled. The disk 11 is also provided with an opening 13 to allow fluid under pressure to enter the inlet port 3. The upper end of the motor casing is provided 10 with an externally threaded screw cap 16 which is adapted to fit in the internal thread of the casing and is also provided with an internally threaded opening to receive the end of a pipe or hose coupling adapted to 15 supply fluid under pressure to the apparatus. The upper end of the motor is provided with a recess or admission chamber 17 to which fluid under pressure is first admitted, and connecting therewith is a cut- 20 out portion or notch 18 on one side of the screw cap to allow free passage of the fluid to the inlet port. The casing is provided with an internal seat 19 adapted to receive the disk 11 and to form a closure therewith. 25 The shaft 20 is provided with a slot 21, the ends of which and particularly the lower end, it will be noted, are removed certain distances from the shoulder in order to give the shaft greater strength by not cutting 30 away its largest diameter, and the junction of the reduced ends of the shaft with the larger body portion are made with considerable fillets, curves or bevels, in order that the upper surface of the eccentric flange 8 and the lower surface of the disk 11 may 35 contact with the ends of the blades, thus obviating any leakage at the ends thereof, while the construction of the shaft thus provides much greater strength than if the slot 40 therein extended to the reduced end portions. The ends of the slot are also rounded in order to obviate the use of square cornered openings, which, in themselves, are a source of weakness, and by reason of this 45 construction my shaft is very much stronger and better adapted for service than the ones customarily in use.

The paddles or blades of the apparatus are 22, each provided with a thickened and 50 rounded end 23, the outer portions of which are adapted to contact with the inner surface of the eccentrically located cylindrical opening or fluid-pressure chamber 2 in the casing, and as illustrated in Fig. 2 the 55 curved connecting portion between the reduced end of the shaft and the larger body portion, as above referred to, is 24, and the upper reduced end of the shaft forming the top journal thereof is 25. The lower outer 60 end of the shaft is threaded, as illustrated, at 27 and adapted to receive an internally threaded eye-bolt 28, which in turn is connected to a similar eye-bolt end 29 of the flue cleaner head 30, thereby forming a uni- 65 versal joint.

It should also be noted that the outer edge of the slot in the shaft is beveled, as illustrated, at 31, in order to more fully protect the ends of the blades and allow them to function properly, while 32 is the rounded 70 thrust bearing surface on the bushing flange 8 as illustrated in Fig. 1.

Referring now to Fig. 9: The shaft 20 is provided, as before, with a smaller cylindrical portion 26 forming a bearing for the 75 lower end thereof, this being connected to the larger body portion by means of the curved fillet 33, which is concave and which fits on the convex rounding 34 of the eccentric flange 8 of the bushing 7.

Referring to Fig. 10: The smaller portion 26 of the shaft 20 is connected thereto by a beveled portion 35 which fits against the correspondingly beveled portion 36 of the eccentric flange 8 of the bushing 7, all 85 of these constructions, including that shown in Figs. 1, 9 and 10, serving as thrust bearings for the shaft 20, and the curved or beveled connection between the two shafts serves to strengthen the junction, particularly on account of the slot 21 which would otherwise weaken the shaft.

On account of the fact that fluid pressure is applied to the upper end of the shaft and not to the lower end, this has a tendency to cause the shaft to press somewhat against the lower end of the apparatus so that the eccentric bushing 7 serves, in a measure, as a thrust bearing and the rounded fillet of same co-operating with the similarly rounded junction between the smaller portion of the shaft and the larger body cooperates with this and together resist the thrust.

The operation of my motor is as follows: 105 Fluid under pressure is introduced from a hose or pipe connected with externally screw-threaded opening in the cap 16, enters the admission chamber 17, thence into the main inlet port 3, then through the cross 110 ports 4 into the cylindrical fluid-pressure chamber 2, where the pressure acts upon the projecting ends of the paddle blades 22 and causes them to rotate, thereby rotating the shaft 20 and its connections, the ends of the 115 paddles 22 meanwhile contacting with the inner cylindrical surface of the fluid-pressure chamber 2, and after a paddle has passed the cross ports 6 the fluid is then exhausted into the exhaust port 5 and is discharged into the outer air, and as the paddles and shaft rotate, this operation is continuous. As compared with prior motors of this general type, my apparatus is of very simple construction, composed of few parts, 120 all of which are easily manufactured and their arrangement is such that the mechanical operations to form them are the simplest possible, all conducing to ease of construction, operation and maintenance.

Although I have described and illustrated my invention in considerable detail, I do not wish to be limited to the exact and specific details thereof, as shown and described, but 5 may use such modifications in, substitutions for, or equivalents thereof, as are embraced within the scope of my invention, or as pointed out in the claims.

Having thus described my invention, what 10 I claim and desire to secure by Letters Patent is:—

1. In a motor of the class described, a casing, a cylindrical fluid pressure chamber eccentrically located therein, a revolute 15 shaft with reduced end portions mounted therein, a rear bearing therefor comprising a disk seated within the chamber, serving as a closure for the portion therebelow, a central perforation in said disk in which the 20 rear reduced end of the revolute shaft is journaled and exposed to the incoming fluid pressure, and a forward bearing comprising an eccentric bushing provided with a flange concentric with the fluid pressure chamber.

2. In a motor of the class described, a casing, a cylindrical fluid pressure chamber eccentrically located therein, a revolute shaft with reduced end portions mounted 25 therein, a rear bearing therefor comprising a disk seated within the chamber and together with the shaft end serving as a closure for the portion therebelow, a central perforation in said disk in which the rear reduced end of the revolute shaft is journaled and exposed to the incoming fluid 30 pressure, and a front bearing for the reduced forward end of the revolute shaft comprising a bushing mounted within the motor casing and provided with an integral eccentric flanged edge concentric with the 35 fluid pressure chamber and forming the entire head of the fluid pressure chamber.

3. In a rotary motor, a casing, a cylindrical fluid pressure chamber eccentrically 45 located therein, a revolute shaft with reduced end portions mounted in said chamber, the rear bearing therefor comprising a disk seated within the casing, and exposed to the incoming fluid pressure and together 50 with the shaft end forming a closure for the working chamber, a central perforation in said disk in which the rear reduced end of the revolute shaft is journaled, a front bearing for the reduced forward end of the 55 revolute shaft comprising a bushing concentrically mounted within the motor casing and provided with an integral eccentric flanged edge concentric with the fluid pressure chamber and forming the entire head 60 of the fluid pressure chamber, a convex bearing surface formed around the inner edge of the bushing, and a bearing surface

formed on the revolute shaft for engaging the convex bearing surface of the inner edge of the bushing.

4. In a rotary motor, a casing, a cylindrical fluid pressure chamber eccentrically located therein, a revolute shaft with reduced end portions mounted therein, the rear bearing comprising a disk seated within the 65 casing, a central perforation in said disk in which the rear reduced end of the revolute shaft is journaled, said disk and shaft end being exposed to the incoming fluid, a front bearing for the forward end of the revolute shaft, comprising a bushing concentrically mounted within the front end of the motor casing and provided with an integral eccentric flanged edge concentric with the fluid pressure chamber and forming the 70 entire head of the fluid pressure chamber, a rounded or convex bearing surface formed around the inner edge of the bushing, a rounded or convex bearing surface formed on the revolute shaft adapted to engage the 75 convex or rounded bearing surface around the inner edge of the bushing, and a removable pin for retaining the flanged bushing in place whereby the said flanged bushing may be removed at will.

5. A rotary motor, comprising a casing, a cylindrical fluid pressure chamber eccentrically located therein, a revolute shaft with reduced end portions mounted therein, the larger central portion of the revolute shaft 90 being formed with a diametrical slot therethrough with rounded ends, paddles or blades seated in the diametrical slot having rounded outer edges and ends, a bearing for the rear reduced end of the revolute shaft 95 comprising a disk seated within the casing, a central perforation in said disk in which the rear reduced end of the revolute shaft is journaled, said disk and shaft end being adapted to receive the thrust of the incoming fluid pressure, a bearing for the forward end of the revolute shaft, comprising a bushing concentrically mounted within the front end of the motor casing and provided with an integral eccentric flanged edge concentric with the fluid pressure chamber and forming the entire head of the fluid pressure chamber, a rounded or convex bearing surface formed around the inner edge of the bushing, a rounded or convex bearing surface formed on the revolute shaft adapted to engage the convex or rounded bearing surface around the inner edge of the bushing, and a removable pin adapted to retain the flanged bushing.

In witness whereof I hereunto affix my signature.

FRED A. ENGH.
